UNITED STATES PATENT OFFICE.

PERCY J. WILLIAMS, OF SAN FRANCISCO, CALIFORNIA.

HOSE CLAMP.

Application filed March 2, 1921. Serial No. 448,988.

To all whom it may concern:

Be it known that I, PERCY J. WILLIAMS, a citizen of the United States, residing at San Francisco, in the county of San Francisco and State of California, have invented new and useful Improvements in Hose Clamps, of which the following is a specification.

The present invention relates to improvements in clamps for securing couplings, nozzles and the like to rubber and other flexible hose.

The primary object of the invention is to provide a hose clamp which will be superior in point of simplicity of construction, inexpensiveness of manufacture and ease and reliability of adjustment, the clamp consisting of but few parts and being capable of effecting a more even and reliable clamping action than the ordinary hose clamp.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawing:

Figure 1 is a front elevation of the clamp as it would appear in use.

Figure 2 is a side elevation of the clamp showing it applied to a hose.

Figure 3 is a perspective view of a detail of the clamp showing a portion of the circular jaw.

Figure 4 is a vertical sectional view of one of the holders.

Figure 5 is a fragmentary perspective view of a modified form of holder.

The clamp of this invention comprises an annular or circular expandable and contractible jaw 1, preferably formed of a single strand of resilient wire. The wire of the jaw is bent into ring or circular form with the end portions 2 thereof doubled upon the main loop or ring 3 and extended nearly around the same, so that the jaw will consist of one complete coil and one nearly

complete coil. I may provide a plurality of complete coils and one nearly complete coil if desired.

The free ends of the wire or jaw are attached to adjustable angular jaw holders 4 and 5, by being inserted through openings 6 in said holders and bent back as at 7 so as to avoid being pulled out of said holders, and provide a secure connection.

The holders 4 and 5 are adjustable towards and away from one another on a screw or bolt 8 which is inserted through apertures 9 in said holders. A screw head 10 is provided on one end of the screw and a nut 11 is turned on the other end so as to engage the holder 4. The holder 4 is provided with flanges 12 which engage opposite faces of the nut and prevent turning thereof. The head 10 engages between similar flanges 13 on the holder 5 but is permitted to turn freely.

Portions 14 of the holders 4 and 5 are curved so as to conform to the curvature of the hose and portions 15 of said holders extend outwardly from the portions 14 and have the apertures 9 therein. The bolt or screw 8 extends at right angles to the portions 15. The inner faces of the portions 14 are grooved as at 16 to receive the jaw 1 whereby cutting of the hose is prevented.

In use, the jaw 1 is fitted around the hose at the desired point and the portions 14 of the holders will engage the hose as shown in Figure 1. By turning the screw 8 with a suitable instrument, not shown, so as to move the holders 4 and 5 toward each other, the ends of the jaw will be pulled together and the jaw will contract and bind or clamp firmly and evenly on the hose. The nut 11 will hold the bolt or screw against unintentional turning and the holders will thus be securely held in adjusted position. The holders are also clamped firmly upon the hose and assist in effecting a firm and reliable gripping or clamping of the hose.

The jaw 1 may be readily loosened and allowed to expand by turning the screw 8 so as to allow the holders 4 and 5 to move away from one another, the spring action of the jaw causing this movement of the holders upon such turning of the screw.

The clamp may be readily and easily assembled or disassembled by reason of its simplicity of construction and novel arrangement of its parts. By provision of

the grooves 16 and the curved portions 14 in the holders the wire of the jaw 1 will lie in such manner as not to present an uneven surface to the extent that cutting or injuring of the hose will result from a tight clamping thereof.

As shown in Figure 5 there may be provided a holding lip 17 struck out from the metal of each holder 18. This lip is to be bent to overlie the free ends 19 of the jaw 20 so as to securely hold the ends in place.

I claim:

1. A hose clamp comprising, a wire loop having overlapping ends, holders having 15 openings therein thru which the ends of the loop are inserted, one of said ends being bent down and back upon the holder, and a clip carried on one of the holders and bent over and upon to hold the bent back portion of wire against pulling out of the opening.

2. A hose clamp comprising a loop having overlapping ends, holders to which said ends are connected, means carried on one 25 of said holders for adjustably clamping upon the holder one end of said loop and means associated with the holders for mov-

ing them towards and away from one another to contract and expand the loop.

3. A hose clamp comprising a loop having 30 overlapping ends, holders to which said ends are connected, one of said holders having an opening therein thru which one of said ends is extended, means on the last named holder for engaging and holding said end of said loop down upon the holder and means for moving the holders towards and away from one another to contract and expand the loop.

4. A hose clamp embodying in its construction a jaw consisting of a single strip 40 of material convolved to provide one complete loop and a part of another loop, holders to which the ends of said material are connected and having faces adapted to engage directly upon a hose, said faces having 45 grooves therein extending through and engaged in which grooves are portions of the complete loop, portions of the strip of material near the ends being extended into said grooves and means for moving said 50 holders so as to contract and expand the jaw.

PERCY J. WILLIAMS.
